UNITED STATES PATENT OFFICE

102,747

DESIGN FOR A BOX

Allan C. Bussey, Minneapolis, Minn.

Application February 24, 1936, Serial No. 61,317

Term of patent 7 years

To all whom it may concern:

Be it known that I, Allan C. Bussey, a citizen of the United States, residing at Minneapolis, in the county of Hennepin and State of Minnesota, have invented a new, original, and ornamental Design for a Box, of which the following is a specification, reference being had to the accompanying drawing forming a part thereof, wherein

The figure is a perspective view of a box showing my new design.

The side and end of the box not shown have substantially the same appearance as the portions shown in the single figure of the drawing.

I claim:—

The ornamental design for a box, substantially as shown and described.

ALLAN C. BUSSEY.
